DESIGN FOR A VEGETABLE HOLDER

Henry S. Cowins, Englewood, N. J.

Application October 21, 1938, Serial No. 80,591

Term of patent 3½ years

To all whom it may concern:

Be it known that I, Henry S. Cowins, a citizen of the United States and a resident of Englewood, in the county of Bergen and State of New Jersey, have invented a new, original, and ornamental Design for Vegetable Holders, of which the following is a specification, reference being had to the accompanying drawing, forming part thereof.

The drawing shows a perspective view of a vegetable holder embodying my new design.

I claim:

The ornamental design for a vegetable holder, as shown.

HENRY S. COWINS.
